Primary Examiner — John Windmuller

CLAIM

The ornamental design for a scraper handle, as shown and described.

DESCRIPTION

FIG. 1 is a perspective view of a scraper handle showing my new design;

FIG. 2 is a front side view thereof;

FIG. 3 is a back side view thereof;

FIG. 4 is a right side view thereof;

FIG. 5 is a left side view thereof;

FIG. 6 is a top plan view thereof;

FIG. 7 is a bottom plan view thereof; and,

FIG. 8 is a perspective view.
